United States Patent Office

Des. 182,877
Patented May 27, 1958

182,877

INDUSTRIAL TRUCK

Nelson E. Cole, Reading, Pa., assignor to Dana Corporation, Toledo, Ohio, a corporation of Virginia

Application December 31, 1956, Serial No. 44,360

Term of patent 14 years

Cl. D14—3)

FIG. 1

FIG. 2

Fig. 1 is a front perspective view of an industrial truck showing my new design; and

Fig. 2 is a rear perspective view of the truck shown in Fig. 1.

I claim:

The ornamental design for an industrial truck, as shown.
